United States Patent Office

Des. 226,284
Patented Feb. 6, 1973

226,284

TRAY

Robert F. Bateman, St. Paul, Minn., assignor to
Plastics, Inc., St. Paul, Minn.

Filed June 9, 1971, Ser. No. 151,625

Term of patent 14 years

Int. Cl. D7—99

U.S. Cl. D44—10 E

FIG. 1

FIG. 2

FIG. 3

FIG. 4

FIG. 1 is a top plan view of a tray, showing my new design;

FIG. 2 is a side elevation view;

FIG. 3 is an end elevation view; and

FIG. 4 is a top perspective view thereof.

The bottom of the design is substantially plain and unornamented.

I claim:

The ornamental design for a tray, as shown and described.
